PROTECTOR MECHANISM FOR LOOMS

Application filed December 14, 1928. Serial No. 325,988.

This invention relates to protector mechanisms for looms and it is the general object of the invention to spare the protector finger the twisting to which it is ordinarily subjected at the time of knock-off and at the same time permit the parts to remain in their properly adjusted position.

The ordinary loom is provided with a protector rod to which is usually welded a protector dagger. The latter cooperates either with a knock-off lever or a frog, depending upon the type of loom, and is positioned by the protector finger. The finger is adapted for engagement with the shuttle binder. The parts are so related that when a shuttle is properly boxed the protector finger, protector rod, and dagger will rock so that the latter will in its forward movement pass to one side of the knock-off lever or frog. When a shuttle is absent, however, the dagger is not moved and engages a loom stopping part to arrest movement of the lay so that the warp may be protected.

In some looms the relation of the center of the lay, the axis of the protector rod, and the part with which the dagger cooperates is such that during forward movement of the dagger at the time of protection there is a change in the angular relation between the path of movement of the knock-off lever or frog and the arcuate movement through which the detecting mechanism moves, and as a result the protector finger has a tendency to change its position with respect to the protector rod.

As ordinarily constructed the protector finger is held to the protector rod in angular adjustment by means of a set screw and it is because of this construction that the protector finger slips on the protector rod. In order to prevent movement of the finger angularly on the rod it has been proposed to provide means for holding the protector finger in fixed angular relation with the protector rod in such a way that the finger cannot slip. With such a construction it is not unusual to employ an adjustable screw in the top of the finger to engage the binder, the screw being movable so that the dagger can be given its proper clearance when the binder

is pushed out by a boxed shuttle. While such a construction prevents the hub of the protector finger from moving angularly with respect to the protector rod there is nevertheless the aforesaid tendency to change the shape of the upper part of the finger due to the changing angular relations between the protector mechanism and the loom stopping element.

In order that this last named strain may be relieved it has been proposed to put a spring between the protector finger and the screw but as previously made the spring has been adjustable as to tension or compression only by changing the relative position of the binder engaging part of the screw and the protector finger. Such constructions are faulty in that a variation in the spring pressure is accompanied by an undesired variation in the angular relation between the effective part of the protector finger and the dagger.

It is an important object of my present invention to provide a protector finger having an adjustable screw which is held in position by a spring but wherein the latter is adjusted as to pressure through an additional element which preserves the proper angular relation between the dagger and the screw while effecting variations in the spring pressure.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a vertical transverse section taken through a portion of the loom showing my invention applied to the protector finger,

Fig. 2 is a detailed enlarged front elevation taken in the direction of arrow 2, Fig. 1, and

Fig. 3 is an end elevation taken in the direction of arrow 3, Fig. 2, certain parts being in section to illustrate my invention.

Referring to Fig. 1 I have shown a loom frame 10 having a breast beam 11 to the under side of which is pivoted or otherwise mount-

ed for relative movement a knock-off lever 12. As shown herein said lever may move around a stud 13 which is fixed to the breast beam. The rear face of the lever is provided 5 with a notch 14 adapted to receive a forward end of a dagger 15 fast with respect to a protector rod 16.

The protector rod may be rotatably mounted in one or more bearings 17 mounted on the 10 lay substantially in the position shown in Fig. 1. It is possible of course that the protector rod may be mounted elsewhere than in the particular location shown herein and I do not wish to be limited to the particular 15 location of the knock-off lever or protector rod set forth.

The protector rod is mounted on the lay L which is supported by swords one of which is indicated at 18. The swords move about 20 a rocker shaft 19 the axis of which is fixed with respect to the frame 10. The lay is provided with a box back 20 which determines the position in shuttle S, while the forward wall of the latter engages a binder 25 21 of usual construction and of itself forming no part of my present invention. The lay and shuttle box are so related that when the lay is in its foremost position the rear wall of the shuttle will ordinarily be directly 30 above the axis of the rocker shaft 19 so that the blow which the reed gives the cloth will be substantially perpendicular to the plane of the latter, the cloth being substantially horizontal.

35 The matter thus far described is of common construction and forms no part of my present invention. It is found with such constructions in certain instances at least that because of the relation between the advancing end of the dagger and the rocker shaft 19 and because of the fact that the knock-off lever moves forwardly in a substantially straight line, the finger changes its angular relation during the time that the dagger is in the notch 14 with the result that the protector rod 16 tends to rotate through a slight angle with respect to the lay during protection.

My invention relates more particularly to the protector finger and the parts carried thereby and in carrying my invention into effect I provide a finger 30 having a hub 31 through which extends a set screw 32. The latter may be received by a rather large 50 notch 33 formed in the protector rod so that the angular position of the hub 31 with respect to the protector rod 16 cannot easily be disturbed and will remain substantially the same throughout the operation of the loom. The finger is formed more particularly as shown in Fig. 3 and has threaded in the upper end thereof a sleeve 34 extending toward the binder. Said sleeve is held in position by a lock nut 35 adapted to engage 55 the upper part of the finger 30. The sleeve

has a smooth internal bore to receive a screw 36 and there is provided a lock nut 37 on the screw to engage the forward or left hand end as viewed in Fig. 3 of the sleeve 34.

The rear end of the screw is provided with 70 a head 38 adapted to engage the binder 21 and there is interposed between the rear of the sleeve 34 in the head 38 a compression spring 39 which tends to keep the screw in rear position with respect to the protector 75 finger.

It is to be understood that there is some 80 form of yielding device tending to hold the protector finger rearwardly and as shown herein such device may be a torsion spring 40 surrounding a portion of the rod 16 and having one end operatively related to the dagger and the other end located under the lay L. The effect of the spring 40 is to lift the dagger 15 so that the same will be normally positioned to enter the notch 14 unless the shuttle acts through the protector finger to move the dagger downwardly against the action of spring 40. As in previously proposed constructions it is necessary that the 90 spring 39 exert a somewhat greater pressure than that exerted by spring 40 so that outward movement of the binder will effect a corresponding movement of the protector finger and dagger.

There is ordinarily only a limited amount 95 of space in which the spring 39 may be located. It is necessary of course that the spring 39 be sufficiently expanded so that it can yield during the action of protection, but it must be stiff enough, as previously stated, to overpower the torsion spring 40. It is desirable to have some form of adjustment which will permit the proper tensioning of spring 39 to accommodate these different conditions but in varying the pressure of the spring 39 the angle defined by the dagger and a line extending from the axis of the protector rod through the rear face of the head 38 should not be changed. This condition is 100 effected by the construction set forth herein.

In operation, at the time of protection, the binder will be in its rearward position, that is, to the right of the position shown in Fig. 1, with the result that the dagger 15 will be 115 raised to enter the notch 14. As the lay continues to move forwardly during the knocking-off of the loom the spring 39 will be compressed due to the previously mentioned changing angular relation between the protector devices and the path of movement of the lever 12. In this way the protector finger 30 is not acted upon by any force sufficiently strong either to alter its shape or to 120 change its angular relation with the protector rod 16.

Due to variations in the picking of the loom the weaver or loom fixer will occasionally change the shape of the binder. Any wear on the part of the rocker shaft 19 will 130

also result in a slight downward movement of the lay and for these and possible other reasons it may become necessary from time to time to change the protector finger or that part which engages the binder. This can be effected by loosening the check nut 37 and moving the head 38 of the screw to the proper position so that when a shuttle is properly boxed the dagger 15 will just clear the notch 14 as the lay moves forwardly. If it be found that the new setting of the screw permits too great expansion of the spring 39 the lock nut 35 can be released and the sleeve moved rearwardly to bring about the correct compression of the spring 39. With this adjustment it will of course be necessary to move the screw 36 forwardly an amount equal to the rearward movement of the sleeve, but this can readily be accomplished by the lock nut 37.

From the foregoing it will be seen that I have provided a protector mechanism wherein the finger may be held against angular movement with respect to the protector rod and that the screw which engages the binder may be kept in its proper angular position with respect to the dagger even though the spring 39 be subject to adjustment. By the construction set forth the tendency to alter the shape or change the angular position of the finger with respect to the protector rod is obviated in a way that will permit the correct positioning of the adjustable element on the protector finger with respect to the binder.

Having thus described my invention it will be seen that changes and modifications may be made therein by those skilled in the art without departing from the spirit and scope of the invention and I do not wish to be limited to the details herein disclosed, but what I claim is:

1. In protector mechanism for a loom having a shuttle binder and a protector rod, a sleeve threaded in the protector finger, a screw slidable through the sleeve and adapted for engagement with the binder, and a compression spring located between the sleeve and that portion of the screw which engages the binder.

2. In protector mechanism for a loom having a shuttle binder and a protector rod, a sleeve threaded in the binder finger and capable of assuming a plurality of longitudinal positions with respect to the finger, a screw slidable through the sleeve, a head formed on the screw adapted for engagement with the binder, and a compression spring located between the sleeve and the head and tending to hold the latter toward the binder.

3. In protector mechanism for a loom having a shuttle binder and a protector rod, a sleeve threaded through the protector finger and movable toward and from the binder, a binder engaging element slidable through the

sleeve, and a resilient device acting on the binder engaging element to permit yielding of the element in the direction in which the binder moves when advancing, said yielding element being positioned by the sleeve.

70

4. In protector mechanism for a loom having a shuttle binder and a protector rod, a sleeve threaded through the protector finger and having an axis projecting toward the binder, a binder engaging element slidably mounted in the sleeve, and a yielding device interposed between the sleeve and the binder engaging element tending to hold the latter toward the binder by permitting forward movement of the element with respect to the finger.

75

5. In a protector mechanism for a loom having a shuttle binder and a protector rod, a protector finger, a movable element deriving its support from the finger and adapted for engagement with the binder, a yielding device tending to hold the element toward the binder, and a supporting member interposed between the movable element and the protector finger and effective to move the element bodily with respect to the finger and having engagement with the yielding device.

80

In testimony whereof I have hereunto affixed my signature.
